UNITED STATES PATENT OFFICE.

CHARLES F. SCOTT, OF NEW HAVEN, CONNECTICUT, ASSIGNOR TO WESTINGHOUSE ELECTRIC AND MANUFACTURING COMPANY, A CORPORATION OF PENNSYLVANIA.

MEANS FOR MINIMIZING INDUCTIVE INTERFERENCE.

1,196,300.

Specification of Letters Patent. Patented Aug. 29, 1916.

Application filed January 2, 1915. Serial No. 170.

To all whom it may concern:

Be it known that I, CHARLES F. SCOTT, a citizen of the United States, and a resident of New Haven, in the county of New Haven and State of Connecticut, have invented a new and useful Improvement in Means for Minimizing Inductive Interference, of which the following is a specification.

- My invention relates to means whereby 10 electric current flow may be substantially confined to certain conducting paths in preference to other paths which may be of low impedance, and which may be electrically connected in parallel relationship therewith. 15 More particularly, my invention relates to means whereby the return flow of trolley currents of a railway system may be substantially confined to the track rails, in preference to ground or earth return. 20 By reason of confining the return trolley current flow to the track rails, inductive disturbances imposed upon other electrical circuits, such as intelligence-transmission circuits which are located in proximity to the 25 railway system, may be greatly minimized or substantially neutralized. Incidentally, electrolytic corrosion of water mains, gas mains, etc. which might be occasioned by the flow of earth currents originating from 30 electrical railway systems, may be substantially eliminated or reduced to negligible amounts.

Inasmuch as the rails comprising tracks of railway systems are more or less in electrical contact with the earth, which is equivalent to a conductor of very low impedance, a considerably large portion of the return trolley currents will ordinarily flow in the earth. As a result, the inductive disturbances set up by the flow of power currents over the trolley are given free play, because the return currents flowing through the earth are so remotely removed from the trolley currents that the inductive effects resulting from the trolley and earth return currents do not neutralize one another to any appreciable extent.

As it is well known, auxiliary conductors independent of the trolley conductor or the 50 rails have been disposed adjacent to railway circuits or intelligence-transmission circuits in order to confine the inducing disturbances occasioned by the trolley currents or to neu-

tralize and minimize the electromotive forces induced in the intelligence-transmission circuits. These results are effected, in the former instance, by confining the flow of the return trolley currents to independent auxiliary conductors which are disposed closely adjacent to the trolley conductors and are 55 electrically connected to the tracks; in the latter instance, by subjecting the inductive auxiliary conductors to the same inductive influences that are imposed upon the intelligence-transmission conductors, the auxiliary 60 conductors and the intelligence-transmission conductors being so interconnected, preferably by transformers, as to counter-balance or substantially neutralize, the electromotive forces induced therein. 70

By means of my invention, the return flow of the trolley currents may be confined to the track rails or in regions of the earth which are closely adjacent to the track rails. In this manner, the zones of disturbing inductive influences arising from the return flow of the power currents are restricted, and such currents are confined to limited regions close to the trolley conductors, whereby the former may be used effectively to minimize 80 or neutralize the disturbances occasioned by the latter.

For a better understanding of the nature and the scope of my invention, reference may be had to the following description and 85 the accompanying drawings in which—

Figure 1 is a schematic diagram showing an embodiment of my invention; Fig. 2 is a diagrammatic view of a system in which my invention is employed in connection with a 90 track that comprises two rails and constitutes the return circuit for the trolley currents; Figs. 3, 4 and 5 are diagrammatic views, showing my invention applied to a railway system in which short track or trolley sections, or both, are interposed between the main portions of their respective circuits in order not to subject the insulating joints to excessive voltages; Figs. 6 and 7 are diagrammatic views of modifications of the 100 systems shown in Figs. 2 and 3; Fig. 8 is a diagrammatic view of a railway system in which the two rails are insulated from each other and are connected inductively to the trolley circuit by independent secondary 105 coils, and Figs. 9 and 10 are diagrammatic

views of modified forms of the system shown in Figs. 1 and 2, respectively.

In a railway system, trolley currents return through the earth because of the difference of potential between that portion of the track near the vehicle and that portion of the track near the sub-station where the power is generated. This difference of potential results from the relatively high impedance 5 of rails which causes a difference of potential between various portions of the track when current traverses the same. If the return trolley current is wholly confined to the track and prevented from flowing through the 10 earth, the electromotive forces induced in an intelligence-transmission conductor equally distant from the trolley and from the track, will be negligible because of the neutralization 15 of the electromotive forces induced in the intelligence-transmission conductor by the trolley current and the current flowing over the track, respectively. The track is a natural path for the return flow of the trolley current, as it is of substantially low 20 resistance and low impedance, and is available in all railway systems. By means of 25 my invention, I propose to confine the flow of return trolley currents to the track by supplying compensating electromotive forces 30 for overcoming the impedance offered by the track.

Referring to Fig. 1, a source of power supply 1, shown as a single-phase alternator, is connected, through one of its terminals, to a trolley conductor 2 and, through another of its terminals, to a rail 3 of a track. Ordinarily, the alternator will have one of its terminals grounded which electrically connects the alternator to the track 35 which is in contact with the earth. A plurality of series transformers 4 are inserted at intervals along the railway system, as shown, primary windings 5 being connected in series-circuit relationship with the trolley 40 conductor 2, and secondary windings 6 being connected to the rail 3 across insulating joints 7. The insulating joints 7 divide the track into a series of insulated sections. An intelligence-transmission conductor 8, shown 45 as a telegraph conductor, is disposed adjacent to the trolley conductor 2 and the track 3 and is, therefore, under the inductive influences arising from the currents flowing over the aforementioned conductors. Ordinarily, when a moving vehicle 9 receives power from the trolley conductor 2, a considerable portion of the return trolley currents flow from the vehicle 9 through ground to the source of power supply 1 which has 50 one of its terminals grounded. In my system, however, the return trolley currents traverse the rails 3. The electromotive forces for sending currents through the rails 3 are supplied by the series transformers 4, 55 the secondary windings 6 of which, as before mentioned, are inserted at intervals in the track circuit. For example, if there is a total electromotive force of 200 volts required for sending the return trolley currents through the portions of the track rails 70 intervening between the vehicle 9 and the source of power supply 1, the series transformers 4 inserted in this portion of the track will supply, in the aggregate, this required total electromotive force of 200 volts. 75 If the above-mentioned portion of the track be four miles long and, if a series transformer 4 is inserted in each mile thereof, then each of the transformers will supply an electromotive force of 50 volts. As electromotive forces are thus impressed by transformers inserted in every mile of the track, 80 there is a substantially uniform distribution of potentials along the track instead of a maximum difference of potential of 200 85 volts. As a result, the current flow in the earth will, in general, be for short distances only between the transformers. The series transformer 4 having primary and secondary windings, preferably of substantially 90 equal numbers of turns, will insure a current flow through the track 3 substantially equal to that through the trolley 2 by reason of the necessity of having the ampere turns in the primary circuit nearly equal to the 95 ampere turns in the secondary circuit of the transformer. Inasmuch as the return flow of the trolley currents is confined to the track 3, which is disposed in proximity to the trolley 2, the inductive effects imposed 100 upon the conductor 8 will be substantially neutralized. Of course, the total electromotive force drop in the railway system will be substantially the same as that which would occur if the transformers 4 were not inserted 105 therein, because the primary windings 5 of the transformers 4 require certain voltages which are equal to those impressed by the secondary windings 6 upon the track rails. 110

If a signaling system is employed on a railway system, it may be necessary to provide inductive bonds connected between the two rails of the track and disposed adjacent to the insulating joints therein in order 115 to create a suitable path for the currents used in operating the signals. In Fig. 2, I have shown inductive bonds 10 inserted at the sides of the insulating joints 7 which are disposed in the track circuit 3. The 120 secondary winding 6 of the transformer 4 is connected to mid-points 11 of the windings of the inductive bonds 10. Inasmuch as equal quantities of return trolley currents will flow in opposite directions through the 125 winding of each inductive bond 10, the impedance offered thereby will be negligible. In this instance, both rails 3 comprising the track constitute the path for the return flow of the trolley currents. 130

If the electromotive forces generated in the secondary windings of the transformers are excessive, the track may be provided with a short insulated section 12, as shown in Fig. 3. By this means, the electromotive force generated in the secondary winding of a transformer 15 is divided between two insulating joints 7. An inductive bond 13 is connected between the two rails 3 comprising the insulated section 12. The mid-point 14^a of a double secondary winding 14 of the transformer 15 is connected to the mid-point 13^a of the winding of the inductive bond 13. The terminals of the double secondary winding 14 are connected to the mid-points 11 of the inductive bonds 10. I have shown the transformer 15 provided with the double secondary winding 14, each coil being wound upon a separate magnetic core 16 which is connected in parallel with the magnetic core associated with the other secondary winding. The magnetic flux generated by the primary coil divides normally into two equal portions each of which flows through one of the magnetic cores 16. When a short circuit is imposed upon one of the secondary windings 14 by reason of the wheels of a passing vehicle momentarily bridging the insulating joints of the short circuit will not act upon the whole secondary winding but will be confined to the respective secondary coil which is thus short circuited, leaving the other secondary coil independent to impress an electromotive force upon the track circuit, as hereinbefore explained. Under these conditions, the electromotive force may be limited in amount by providing that the core of the transformer becomes saturated.

In Fig. 4, I have shown the trolley conductor 2 provided with a short insulated section 17 which corresponds to the insulated section 12 in the track of Fig. 3. In this instance, a primary winding 18 comprises two coils disposed on independent core members 19 and having their mid-point 18^a connected to the short insulated trolley section 17. The terminals of the primary winding 18 are connected to the trolley 2 adjacent to insulating joints 20 inserted in the trolley. In this manner, the electromotive force of the primary winding 18 is impressed upon two insulating joints 20 which are connected in series relationship. The secondary winding 6 of the transformer is connected to the track circuit 3, as shown in a similar manner in Fig. 2. The primary winding 18 is divided into two coil sections wound on independent core members so that, when a short circuit occurs upon one of the coil sections as a result of the passing of the contact member of a moving vehicle, this short circuit will not be impressed upon the entire primary winding.

In Fig. 5, I have shown both the trolley 2

and the track rails 3 provided with short insulated sections 17 and 12, respectively. In this instance, both the primary winding 18 and the secondary winding 14 comprises double coil sections, each winding embracing independent core members 19 and 16, respectively. The mid-point 18^a of the primary winding is connected to the insulated trolley section 17, as explained in Fig. 4, and the mid-point 14^a of the secondary winding is connected to the mid-point of the winding of the inductive bond 13 inserted in the short insulated track section 12, as explained in connection with Fig. 3. I prefer to have alternate coils upon the transformer connected together, as shown in the drawing, in order that a transformer of an efficient design may be made. As previously explained in reference to Figs. 3 and 4, the terminals of the primary winding are connected to the trolley conductor 2 adjacent to the insulating joints 20, and the terminals of the secondary winding are connected to the track rails 3 adjacent to the insulating joints 7.

In Fig. 6, the two insulated joints 7 inserted in the rails 21 which comprise the track circuit are staggered, and conducting bonds 22 are inserted in order to connect electrically the two rails in parallel relationship. The terminals of the secondary winding 6 of the transformer 4 are connected to the bonds 22, as hereinbefore explained. As the contact member of a moving vehicle approaches an insulating joint 20 in the trolley conductor 2, and after one of the track insulating joints 7 has been passed by the vehicle, the two rails 21 will be connected electrically because of the electrical connection existing between a pair of wheels of the vehicle. The circuit thus established will continue until after the joint 20 in the trolley conductor has been passed by the contact member and the other joint 7 in the track circuit has been passed by the vehicle, when the connection between the two rails will be broken. At this instant, current will flow in both coils of the transformer 4, the trolley current flowing through the primary winding 5, and the return current flowing through the secondary winding 6. By thus insuring a substantially simultaneous flow of current through both windings of the transformer, the transformer is not subjected to abnormal magnetic saturation and resulting high voltage which would obtain if current flowed through only one coil for a short time.

If it is desired to distribute the voltages impressed upon the track rails over two or more insulating joints as explained in reference to Fig. 3, the system shown in Fig. 7 may be used, to which reference may now be had. The insulating joints 7 inserted in both rails of the track are staggered and

provide a short insulated track section 23, the rails thereof being electrically connected to each other by the conducting bond 22 which, in turn, is connected to the mid-point 14^a of the double secondary winding 14 of the transformer. The terminals of the secondary winding 14 are connected to other conducting bonds 22 which are disposed outside of the short insulated track section 21. 10 The primary winding 5 of the transformer is connected across the insulated joint 20 in the trolley conductor 2. Again, I prefer to dispose the coil sections of the secondary winding 14 on independent core members in 15 order that the transformer shall not be rendered totally ineffective when one of the secondary coils is short circuited. Of course, it will be understood that, in actual installations, the spacing and dispositioning of 20 the insulating joints in both the trolley conductor and the track circuit utilized in the systems above described, are dependent upon the design of the locomotives, such as the relative positions of the contact members and the tracks, and upon the signaling 25 systems employed.

It may be necessary to maintain the two rails comprising a track independent of each other, as is sometimes required for 30 signaling purposes. In Fig. 8, the two rails 21 are insulated from each other, independent secondary windings 24 being connected across insulating joints 7 inserted in each rail. Both independent secondary windings 35 24 are inductively related to the primary winding 5 which is connected in circuit with the trolley conductor 2. In order to adjust the quantity of return current flowing in each rail, each of the secondary windings 40 24 is provided with a plurality of adjustable taps, as shown in the drawing.

In installing my system for confining the return flow of trolley currents to the rails, it may be essential to provide a number of 45 adjusting means to compensate for the irregular spacing of the intelligence-transmission conductor 8 relative to the railway system. For this reason, it may be desirable to provide the primary and secondary 50 windings of the transformers, which interconnect the trolley conductor and the track circuit, respectively, with unequal numbers of turns so as to force a certain amount of the return trolley currents to flow through 55 the earth in the nature of a secondary load, in addition to the magnetizing currents of the transformers. These earth currents may induce electromotive forces in either direction in the telegraph circuit 8, and 60 hence may be utilized for correcting or neutralizing certain other electromotive forces which may be induced therein by reason of the unequal spacing of the telegraph circuit from the trolley conductor 65 and the track circuit.

While a proper adjustment of the relative turns in the primary and secondary windings of the transformers may greatly reduce disturbing influences in the telegraph circuit 8, it may frequently be desirable to adjust the phase relationship of the ground currents. To this end, the secondary windings 6 of Fig. 9, which windings are shown adjustable, are provided with artificial loads each comprising an adjustable resistor 25 75 and an adjustable inductance device 26 which, in this instance, are shown as being connected in series relationship across the active turns of each winding 6. The auxiliary circuits, comprising the resistors 25 and the inductors 26, correspond to the ground circuit, and the phase and current conditions obtaining within these auxiliary circuits are responsible for regulating the phase and current conditions obtaining in the ground 85 circuit. While, in Fig. 9, I have shown the transformers 4 connected in circuit as previously explained in reference to Fig. 1, the secondary windings 6 of the transformer 4 may be connected to the track rails 3 by 90 means of inductive bonds 10, as shown in Fig. 10. In this instance, artificial loads are provided for the adjustable secondary windings 6, as explained in reference to Fig. 9.

From the foregoing, it will be apparent 95 that transformers may be employed in a railway system which have various ratios between the turns of the primary and secondary windings for the purpose of controlling locally the amount of earth currents 100 and the resulting induction in adjacent intelligence-transmission circuits when the latter vary in their position with respect to the railway system.

While I have shown and described in detail several embodiments of my invention, it will be understood by those skilled in the art that many modifications may be made without departing from the spirit and scope of the appended claims.

I claim as my invention:

1. The combination with a conductor of an independent electrical circuit, of an electrical distributing system in close proximity thereto which comprises a source of current supply, a conductor connected to one terminal thereof, a second conductor in contact with the earth connected to the other terminal thereof, and means for transferring the impedance of said second conductor to the 115 first conductor whereby the inductive influences arising from said distributing system and impressed on said independent conductor may be substantially minimized.

2. The combination with an intelligence-transmission conductor, of an electrical distributing system in inductive relation thereto which comprises a source of current supply, a conductor insulated from the ground connected to one terminal thereof, a second 125 130

conductor in contact with the earth connected to the other terminal, and means serving to confine the return current flow to said second conductor in preference to the earth whereby the inductive effects impressed upon said intelligence-transmission conductor may be substantially neutralized.

3. The combination with an intelligence-transmission conductor, of a system of electrical distribution in inductive relation thereto which comprises a source of current supply, a conductor insulated from the ground and connected to one terminal thereof, a second conductor in contact with the earth and connected to the other terminal, and means serving to transfer the impedance drop from said second conductor to the first conductor whereby the current flow through said second conductor may generate electromotive forces to neutralize those impressed on said intelligence-transmission conductor by the current flow through said first conductor.

4. The combination of an intelligence-transmission conductor, of a railway system in inductive relation thereto which comprises a source of current supply, a trolley conductor connected thereto, track rails in contact with the earth, and means serving to impress electromotive forces at intervals in the track rails whereby the inductive effects arising from the current flow in said trolley conductor may be substantially neutralized by confining the return current flow to said track rails.

35 5. The combination with an intelligence-transmission conductor, of a railway system in inductive relation thereto which comprises a source of current supply, a conductor connected to one terminal thereof for the transmission of power currents, a second conductor constituting a track in contact with the earth, and means to impress electromotive forces at intervals in the said second conductor to compensate for the impedance of the track whereby the current flow in said second conductor will be maintained sufficiently high to effectively neutralize the magnetic effects arising from the current flow in said first conductor.

50 6. The combination with a conductor of an electrical circuit that is susceptible to inductive disturbances, of a system of electrical distribution in inductive relation thereto which comprises a source of current supply, a conductor insulated from ground for the transmission of power currents, a second conductor in contact with the earth, a power consumer connected between said conductors, and means serving to confine substantially the return current flow to said second conductor in order to minimize the resultant inductive disturbances impressed upon said conductor of the independent electrical circuit.

65 7. The combination with a conductor of

an intelligence-transmission circuit, of an electrical distributing system in inductive relation thereto which comprises a source of current supply, a conductor insulated from the ground connected thereto, a second conductor constituting a track provided with a plurality of spaced insulating joints, windings connected to the track across said insulating joints, and means serving to induce electromotive forces in said windings in order to compensate for the impedance of said second conductor whereby the resultant induced electromotive forces impressed upon said intelligence-transmission conductor by reason of the current flow in said distributing system may be substantially minimized.

8. The combination with a conductor of an independent electrical circuit, of a system of electrical distribution in inductive relation thereto which comprises a source of current supply, a conductor connected thereto and insulated from the ground, a second conductor in contact with the earth, and means associated with said first conductor to compensate for the impedance of said second conductor whereby the impedance of said second conductor may be reduced to permit a return current flow therein which substantially neutralizes the electromagnetic disturbances impressed upon said independent electrical conductor by the current flow in said insulated conductor of the distributing system.

9. The combination with an intelligence-transmission circuit conductor, of a railway system in inductive relation thereto which comprises a source of current supply, a trolley conductor, track rails, a plurality of spaced insulating joints inserted in the track rails, and transformers inductively interlinking the trolley conductor and the track rails, windings on the transformers being connected to the track rails across said insulating joints and other windings on the transformers being connected at corresponding points in series circuit relationship with the trolley conductor whereby the resultant induced electromotive forces impressed upon said intelligence-transmission conductor may be substantially neutralized.

10. The combination with an intelligence-transmission conductor, of a railway system in inductive relation thereto which comprises a source of current supply, a trolley conductor, a track comprising a plurality of insulated rail sections, and a plurality of transformers inductively interlinking the trolley conductor and the track rails, the primary windings of the transformers being inserted at intervals in series circuit with the trolley conductor and the secondary windings being connected to adjacent insulated rail sections whereby the resultant electromagnetic influences that may be im-

pressed upon said intelligence-transmission conductor are substantially neutralized.

11. The combination with an intelligence-transmission circuit, of a railway system in close proximity thereto which comprises a source of current supply, a trolley conductor connected thereto, a track comprising parallel rails, insulating joints inserted in the rails, and means connected across said insulating joints to inductively link said track rails with the trolley conductor whereby the return current flow may be utilized to minimize the inductive disturbances that may be impressed upon said intelligence-transmission conductor.

12. The combination with an intelligence-transmission conductor, of a railway system in inductive relation thereto which comprises a source of current supply, a trolley conductor connected thereto, a track comprising parallel rails, insulating joints inserted in the rails, and spaced transformers inductively interlinking the trolley conductor to the track rails, primary windings on the transformers being connected in series-circuit relationship with the trolley conductor and secondary windings of the transformers being connected across said insulating joints of the track rails whereby the return current flow may be confined to the track in order that the resultant inductive disturbances impressed upon said intelligence-transmission conductor may be substantially minimized.

13. The combination with an intelligence-transmission conductor, of a railway system in inductive relation thereto which comprises a source of current supply, a trolley conductor connected thereto, a plurality of rails constituting a track, insulating joints inserted in the rails, electrical connections adjacent to said insulating joints to connect the rails in parallel relationship, and a transformer having a primary winding inserted in series with said trolley conductor and a secondary winding connected to said electrical connections between the rails whereby the return current flow confined to the rails may substantially neutralize the inductive effects arising from the current flow in the trolley conductor.

14. The combination with an intelligence-transmission conductor, of a railway system in inductive relation thereto which comprises a source of current supply, a trolley conductor connected thereto, a plurality of rails constituting a track, insulating joints inserted in the rails, electrical connections on each side of said insulating joints to connect the rails in parallel relationship, and a transformer having its primary winding inserted in series with said trolley conductor and a secondary winding connected across said insulating joints and to said electrical connections between the rails whereby the current

flow in said rails may be utilized to neutralize the inductive disturbances arising from the current flow in said trolley conductor.

15. A railway system comprising a source of current supply, a trolley conductor for the transmission of power currents, a track conductor, insulating joints inserted in at least one of said conductors to provide a relatively short insulated conducting section, and a transformer having a plurality of inductively related windings one of which is connected in series with one of the conductors and the other of which is connected to the other conductor and across said insulated section.

16. A railway system comprising a source of current supply, a trolley conductor for the transmission of power currents, a track conductor, insulating joints inserted in at least one of said conductors to provide a relatively short insulated conducting section, and a transformer having a plurality of inductively related windings one of which is connected in series with one of the conductors and the other of which is connected to the other conductor and across said insulated section, a mid-point on the said second transformer winding being connected electrically to said insulated section.

17. A railway system comprising a source of current supply, a trolley conductor for the transmission of power currents, a track conductor, insulating joints inserted in both of said conductors to provide relatively short insulated conducting sections, and a transformer having a plurality of inductively related windings one of which is connected to the trolley conductor outside of said insulated trolley conductor section and another of which is connected to the rail conductor outside of said insulated rail section.

18. A railway system comprising a source of current supply, a trolley conductor for the transmission of power currents, a track conductor, insulating joints inserted in both of said conductors to provide relatively short insulated conducting sections, and a transformer having a plurality of inductively related windings one of which is connected to the trolley conductor outside of said insulated trolley conductor section, and another of which is connected to the rail conductor outside of said insulated rail section, mid-points on each of said windings being connected to the respective insulated trolley and rail conductor sections.

19. A railway system comprising a source of current supply, a trolley conductor for the transmission of power currents, a track conductor, insulating joints inserted in at least one of said conductors to provide a relatively short insulated conducting section, and a transformer having a plurality of inductively related windings one of which is connected in series with one of the conductors

and the other of which comprises a plurality of coils that are connected in series relationship with one another, each of said coils being mounted on independent core legs of the
5 transformer, said series-connected coils being connected to the other conductor across said insulated section, and a mid-tap on the winding comprising the plurality of coils being

connected electrically to said insulated section.

10

In testimony whereof, I have hereunto subscribed my name this 23rd day of Dec., 1914.
